VENDING MACHINE

Louis H. Morin, New York, N. Y., assignor to The Coca-Cola Company, Wilmington, Del., a corporation of Delaware

Original application September 8, 1934, Serial No. 743,255. Divided and this application June 6, 1935, Serial No. 25,336

4 Claims. (Cl. 194—1)

The invention relates to vending machines particularly to vending machines for bottled goods, this application being a division of my application Serial Number 743,255, filed September 8, 5 1934, for patent on Vending machine.

It is an object of the invention to provide means effecting the delivery of a bottle under control of coin controlled mechanism.

It is a further object of the invention to provide 10 means actuated in the absence of a bottle in position to be delivered, preventing the insertion of a coin.

Further objects of the invention will appear from the following description when read in connection with the accompanying drawings showing an illustrative embodiment of the invention, and wherein:

Fig. 1 is a perspective view of the apparatus.

Fig. 2 is a fragmentary elevation showing the 20 cover or closure sections in open relation.

Fig. 3 is a vertical sectional view on line 3—3 of Fig. 5.

Fig. 4 is a detail perspective of certain parts 25 preventing deposit of a coin when the apparatus is empty.

Fig. 5 is a vertical section at right angles to Fig. 3 on line 5—5 of Fig. 3.

Fig. 6 is a horizontal section on line 6—6 of Fig. 3, particularly showing a clutch or coupling 30 mechanism to operate the machine under coin-control.

Fig. 7 is a view substantially similar to a portion of Fig. 6 but showing the clutch or coupling mechanism released as at the start of an 35 operation.

Fig. 8 is a horizontal section on line 8—8 of Fig. 3 showing a driving mechanism.

Fig. 9 is a detail perspective of the drive shaft 40 and pinion with some of the parts in separated relation.

Fig. 10 is a fragmentary side elevation with parts broken away, showing the discharge, and "empty" control.

Fig. 11 is a detail section on line 11—11 of Fig. 45 10.

Fig. 12 is a detail vertical section on line 12—12 10.

As shown the apparatus comprises a suitable 50 portable cabinet 32, adapted to be appropriately supported, interiorly of which is a tank 33, and between which tank and the cabinet walls, suitable insulation 34 is provided. The tank 33 is open at the top and is secured to the inturned 55 upper flange 35 of the cabinet 32 at 36 as shown,

forming a properly insulated rectangular double wall structure.

The tank 33, as best shown in Fig. 3, is provided with a drain pipe 37 communicating with a fitting 38, the discharge from which drain pipe is controlled by means of a petcock 40 at an outlet 41. Said tank is adapted to be filled with 5 iced water and this drain construction is equipped to control the level of the cooling water within the tank.

In the construction illustrated in Fig. 3, at the 10 top of the closure or cover 42 on the edges thereof, there is an inturned bead 43 which holds a covering sheet 44 of linoleum or other suitable 15 material in place. Said cover 42 is double walled as sheet 44 is supplemented by a wall at 45 and suitable insulation 46 is disposed between these 20 walls. Mounted on the inturned edge 35 is a rubber breaker strip or gasket 47 adapted to receive the extended edge of the cover 42 and to 25 form a seal therewith when the cover is in closed position. There is an additional cover 48 affording access to the interior of the tank 33 for inspection and re-icing, such cover 48 having a handle 49 and a lock 50.

The front cover 42 is mounted on four swingable 30 links 53 connected by pivots 54 on the under side of said cover and by pivots 55 on the interior of the tank 33.

On the walls of the tank 33 (Figs. 3 and 5) near 35 the bottom thereof are four supports 73 having horizontal portions 74 adapted to removably support, by means of bolts 75, a chassis for the bottle conveying mechanism, such chassis being designated as a whole by the numeral 76. This 40 chassis is a skeleton metallic frame having four bolt-receiving lugs 77 provided with openings 45 cooperating with bolts 75 to removably secure the chassis to the supports 73.

The mechanism for holding and covering the 50 bottles to be vended is essentially a chain conveyor and consists of a plurality of receptacles 98, each one of which comprises bottle holding cups 99 and 100, formed of a single stamping. The vertical sides of the bottle holding cups are cut 55 away as at 104, in order to enable free circulation of the cooling water through the bottle cups and also to reduce the resistance of the cooling water against the travel of the conveyor through such cooling water.

The chain conveyor carrying the receptacles 99 and 100 is driven by a sprocket, not shown, mounted on hollow shaft 123, which is releasably or detachably keyed at its upper end by means of a key 125 to a second shaft 126 rotatably mount- 55

ed in a bearing 121. The key 125 engages a slot 128 in the shaft 126 in normal operating position, and permits relative vertical movement of the shafts 123 and 126 while still coupled for rotation, 5 as set forth later.

As best shown in Fig. 3, the said shaft 126 has integrally formed therewith an annular plate or disc member 129 depending from which are a series of cams 130. Mounted upon said member 10 129 is a gear 131 having external teeth 132 which in turn mesh with a gear 133 carried by a shaft 134 mounted in a suitable bracket 135 attached by supports 136 to the interior wall of a dome or housing 137 and in an adjustable bearing 135' 15 supported also by said housing 137. Said shaft 134 carries a bevel gear 138 which is normally adapted to rotate freely about or loose on such shaft 134, but which can be, through the medium of a clutch mechanism 139, made to drive the 20 shaft 134. The said gear 138 meshes with a bevel gear 139' mounted upon and rotatable with a shaft 140 which extends through to the front of the casing 137 where such shaft 140 is provided with an operating handle 141.

25 The front of the casing 137 is provided with a coin slot 142 adapted for the insertion of a coin of the proper denomination for the price of the article to be vended. Insertion of a coin in such slot 142 followed by manual turning of 30 the handle 141 in a clockwise direction, operates conventional coin-controlled mechanism which forms no portion of the present invention except as described hereinafter. A coin controlled mechanism which may be employed, is disclosed 35 in Letters Patent No. 2,015,351, issued to me on September 24, 1935.

The operation just described causes the coin-controlled mechanism to function and a continuous movement of the handle 141 moves or causes 40 a detent member 143 to swing against the tension of a spring 144 to release contact with and move out of the path of an extension 145 of a pawl 146 to trip the pawl against the tension of a spring 147.

45 Said pawl 146 serves as a coupling or clutch means to control operation of the machine by the handle 141. Such pawl 146 is pivotally mounted by a shaft 150 to the free end of a bracket member 150' which is fixed to shaft 134. 50 Secured to the lower end of said shaft 150 is an abutment 149' which in operative position is engaged by one of a series of studs 149 carried on the upper face of the bevel gear 138, when detent 143 has disengaged pawl 146.

55 An extension 148 is provided on pawl 146 and engages a stop 148' on bracket member 150' to ensure engagement of abutment 149' and one of the studs 149 through arcuate alinement.

When the various parts are in their operative 60 positions as shown in Fig. 6, shaft 140 and gear 139' are rotated by means of handle 141 and in turn rotate gear 138. One of the studs 149 engages the abutment 149', and rotates the entire clutch mechanism, through the medium of bracket 150', thereby rotating shaft 134 and shaft 126 through gears 131 and 133.

When the coin mechanism is at rest or in inoperative position, the member 143 contacts extension 145 of pawl 146 and holds abutment 149' 70 out of the circle of the studs 149 against the action of spring 147, so that if handle 141 is turned, gear 138 will rotate idly on shaft 143. Upon completion of the complete revolution of gear 138, cam 145 again engages member 143 75 which has returned by operation of the coin-

controlled mechanism to its original position and holds the clutch mechanism in idling position.

The aforesaid cams 130 are timed to engage an anti-friction roller 151 carried by a shaft 152 5 slidably mounted within a bearing 153 and having a vertical slot 154 at its lower end detachably engaging a transverse pin 155 mounted on a stub shaft 156 normally held in extreme vertical position in a bearing 157 by means of a coil spring 158 compressed between the bearing 157 and an 10 annular member 158' carried by the shaft 156.

Said shaft 156 is pivotally connected at 159 Figure 5, to a bottle-ejecting yoke 160 pivotally mounted at 161 and 162, such yoke carrying a 15 pair of fingers 163 located so that during the latter part of their upward travel they are directly in line with the slots 105 in the bottom of either cup 99 or 100 as the case may be.

Directly above the bottle to be vended by the apparatus, the cover 42 has a discharge opening 164 protected by an annular metal casing or ring 165 which carries a disc 166 of sheet rubber or other suitable material, having a small central opening 167 around which the disc 166 20 is slit radially to form V-shaped segments which taper toward the opening 167.

Below the ring 165 is a guard member designated as a whole by the numeral 169 and comprising a depending annular skirt 170 provided with a pair of slots or openings 171 in line with the transverse path of travel of the bottles 172 25 on the front stretch of the conveyor as they travel toward the discharge opening.

The purpose of this member 169 is to prevent 30 the unauthorized removal of a bottle through the discharge opening by insertion of the fingers through such discharge opening prior to the discharging operation of the bottle as shown in dotted lines in Fig. 10.

To prevent deposit of a coin when there are 35 no bottles contained within the machine, means are provided as follows: A bar 173 extends parallel with the front line of bottles nearest the point of discharge and is pivotally mounted on a horizontal axis to guard 170 as at 174, extending between said guard and a guide 175' carried by said guard and is provided adjacent the discharge opening 164, with a horizontally disposed leaf 175 of a length to engage the tops of at least two of the oncoming bottles which maintains the bar 173 normally horizontal. In the absence of a bottle beneath leaf 175, the right-hand end of bar 173 lowers, Fig. 5, and the left-hand end of such bar 173 raises, also raising a bar 176, due to the contraction of a spring 177, 40 attached to bar 176 and casing 137, member 176 45 carrying a link 178, see Fig. 4.

Bar 176 is pivotally connected at 176' to a link 178, journaled at 178' in a bracket 178" on casing 137 as shown in Fig. 6, thus enabling a terminal 179 of said link, when the machine is empty, to enter an opening 180' in the coin-controlled mechanism and intercept movement of a horizontally movable slide 179' of that mechanism to the left in Fig. 6, which movement is 50 essential to enable slide 179' to uncover the coin deposit slot 142, the specific construction of such coin-controlled mechanism otherwise forming no part of the present invention. Thus the raising and lowering of bar 176 respectively rocks link 55 178 into and out of opening 180' and the path of return movement of slide 179'. Broadly expressed, bar 173 lowers at its right-hand end, Fig. 5, when the machine is empty as there are no bottles beneath leaf 175 to keep it raised and ter- 60

5 minal 179 enters opening 180' and intercepts return of the slide 179', and hence prevents uncovering of coin slot 142 by that slide.

In the absence of a coin in the slot 142, the handle 141 may be revolved freely without operating the vending mechanism, as turning of the handle 141 will rotate shaft 140 and the gear 139 carried thereby and consequently the bevel gear 138 only. Said bevel gear 138 moves freely about the shaft 134 because the abutment 149' is out of the path of movement of the studs 149 and consequently no clutching action takes place.

10 Upon the insertion of a coin in slot 142 and a subsequent rotation of handle 141, the coin-controlled mechanism operates and releases or retracts detent member 143 from contact with pawl element 145, whereupon spring 147 moves the clutch pawl 146 toward shaft 134 thereby placing abutment 149' in the same circle with the studs 20 149 on gear 138. Continued rotation of the handle 141 causes the adjacent stud 149 to engage said abutment 149' which couples gear 138 to shaft 134 through bracket 150'. As shaft 134 revolves, it drives through the medium of gear 133, the gear 25 131 enmeshed therewith which carries with it the disc 129 imparting rotation also to shafts 126 and 123 which imparts motion to the entire conveyor.

30 Upon the start of an operation there is no bottle in line with discharge opening 164 and the adjacent bottle cannot be reached by the fingers because of guard 170.

35 As the conveyor brings a cup containing a bottle to be vended close to the discharge opening 164, one of the cams 130 engages the roller 151 on shaft 152 to impart a downward motion against the tension of spring 152' to the latter shaft which in turn is transmitted to shaft 156, which by means of its pivoted connection 159 40 40 with the yoke 160, causes such yoke to rock on its axis 161 and impart vertical movement to the discharge fingers 163, which by this time are aligned with the slots 105 in the bottom of the bottle-containing cup now directly beneath the 45 discharge opening 164.

Continued rotation of the handle 141 causes the fingers 163 to rise through slots 105 into the cup, lifting and supporting the bottle in such cup partly ejected in the discharge opening 164 50 as shown in dotted lines in Fig. 10. During such upward movement of the bottle 172, it passes through disc 166 and pushes apart the segments 168 so that the bottle may then be removed by hand, the bottle being wiped by the said segments.

55 The parts just referred to for the discharge operation remain in this position until the next vending operation is started when the engaging cam 130 disengages the shaft 158 for operating the discharge mechanism and the parts return to normal position to repeat the operation just described.

The bottles 172 maintain bar 173 level and upon the exhaustion of the bottles from the apparatus, the right-hand end of bar 173 will lower 60 due to the contraction of spring 177, resulting in the raising of bar 176 and rocking of link 178

so that its terminal 179 enters opening 180' and intercepts the return of slide 179', thus preventing such slide from uncovering the coin slot 142, until the machine has been refilled with bottles.

Various changes may be resorted to within the 5 spirit and scope of the invention as defined by the following claims.

I claim:

1. A machine of the class described having coin-controlled means operable to release a bottle 10 or the like, and mechanism under control of the bottle being vended operable automatically to prevent insertion of a coin in the absence of an article to be vended comprising a tubular guard having a bottle-entrance opening, a pivoted element on said guard having a portion in the line of discharge movement of bottles or the like to engage and rest on the upper ends of advancing bottles, and a means urging lowering of the element at the bottle engaging end thereof, a bar 15 actuated by said element, a rocker link actuated by the bar, and a slide governing the deposit of coin, into and out of the path of movement of which said link is rocked.

2. A device of the class described having a discharge opening, a generally tubular guard, said guard having an entrance opening for bottles or the like, said guard being in the line of movement of the bottles or the like to said discharge opening, conveyor means to advance bottles through 30 said opening, a pivoted element having a portion exteriorly of said guard and in the said line to rest on the upper ends of the advancing bottles, coin-controlled means to operate said conveyor means having a coin-deposit slot, and means effective to move said element to close said slot in the absence of bottles.

3. A device of the class described having a discharge opening, a generally tubular guard, said guard having an entrance opening for bottles or the like, said guard being in the line of movement of the bottles or the like to said discharge opening, conveyor means to advance bottles through said opening, a pivoted element having a portion exteriorly of said guard and in the said line to 40 rest on the upper ends of the advancing bottles, coin-controlled means to operate said conveyor means having a coin-deposit slot, and means effective to move said element to close said slot in the absence of bottles, said portion having a lat- 45 erally extending guide leaf at the top thereof directly engageable at its under surface with the upper ends of the bottles.

4. A machine of the class described having coin-controlled means operable to release a bottle 55 or the like, and mechanism under control of the bottle being vended operable automatically to prevent insertion of a coin in the absence of an article to be vended comprising a guard having a bottle entrance opening, an element on said 60 guard having a portion substantially in line with said opening to engage bottles and rest on portions thereof, and means urging movement of the element at the bottle engaging portion thereof under coin-control.

65 LOUIS H. MORIN.
